UNITED STATES PATENT OFFICE.

FRANK EGON NEITZEL, OF SAN FRANCISCO, CALIFORNIA, ASSIGNOR TO BETHLEHEM SHIPBUILDING CORPORATION, LTD., OF SOUTH BETHLEHEM, PENNSYLVANIA, A CORPORATION OF DELAWARE.

MACHINE FOR FACING PROPELLER BLADES.

1,426,091.

Specification of Letters Patent. Patented Aug. 15, 1922.

Application filed October 16, 1919. Serial No. 330,978.

To all whom it may concern:

Be it known that I, FRANK EGON NEITZEL, a citizen of the United States, residing in the city and county of San Francisco, State of California, have invented a new and useful Machine for Facing Propeller Blades, of which the following is a specification.

My invention comprehends a novel construction of a machine for facing propeller blades which can be readily adapted to various pitches of different propellers and which is capable of taking care of a plurality of blades at the same time.

It further comprehends a novel construction and arrangement of clearance mechanism.

It further comprehends a novel construction and arrangement of a support, novel means for securing a propeller on the table, novel means to effect the oscillation of the table, a novel construction and arrangement of a tool carrying head and novel mechanism for actuating the tool carrying head.

Other novel features of construction and advantage will hereinafter more clearly appear in the detailed description and the appended claims.

For the purpose of illustrating my invention, I have shown in the accompanying drawings a preferred embodiment which is at present preferred by me, since said embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a front elevation, partly in section, of a propeller blade facing machine, embodying my invention.

Figure 2 represents, in side elevation, a portion of the machine.

Figure 3 represents a section on line 3—3 of Figure 1.

Figure 4 represents a fragmentary sectional view, partly in elevation, of certain parts seen in Figure 3.

Figure 5 represents a perspective view of a spacing collar employed.

Figure 6 represents a section on line 6—6 of Figure 1.

Figure 7 represents a fragmentary section, partly in elevation, showing certain details of construction.

Figure 8 represents a section on line 8—8 of Figure 2.

Figure 9 represents a vertical section, partly in elevation, of the supporting bearing for the tool head.

Figure 10 represents a section on line 10—10 of Figure 9.

Figure 11 represents a section of one of the horizontally disposed members of the tool head for carrying the tool post and cutting tools.

Figure 12 represents a section on line 12—12 of Figure 11.

Similar numerals of reference indicate corresponding parts in the figures.

Referring to the drawings.

I have preferred to illustrate my novel construction of propeller blade facing mechanism in conjunction with a vertical boring mill of standard construction. The revolving table of the boring mill is first removed and an oscillating worm gear 1 substituted for it. Brackets 2 are secured to the frame 3 of the mill around the gear 1 in order to take up any unequal thrust or strain from the cutting tools. The worm gear 1 is provided with an extension hub 4 which fits the inside of the pivot bearing 5 for the revolving table of the boring mill. The worm gear 1 is counterbored on its upper side, as at 6, to receive the lower end of a tapered bushing 7, which is inserted in the hub 8 of the propeller 9 to be faced, whereby said propeller is accurately centered, it being understood that the work, such as the propeller, is fastened to the worm wheel 1 by suitable clamps and braces (not shown) as will be apparent to those skilled in this art.

The worm wheel 1 is driven by the worm 10 carried on a shaft 11 and is mounted in suitable brackets 12 secured to the bed plate 3 of the boring mill.

13 designates a spur gear mounted on the shaft 11 and meshing with a gear 14 mounted on a shaft 15. 16 designates a spur gear mounted on the shaft 15 and in mesh with a pinion 17 mounted on the shaft 18 which latter is the regular table drive for the boring mill. 19 designates a shaft on which the gear 20 is mounted, said gear 20 being in mesh with the gear 14 and also in mesh with

a gear 21, it being understood that said gears 13, 14, 20 and 21 are constructed suitable for the pitch of the propeller and are installed between the worm gear 10 and the 5 regular table drive for the boring mill.

The boring head is driven from the gear 21 which is mounted on the same shaft as a miter gear 22 which in turn is adapted to mesh with either the upper gear 23 or the 10 lower companion gear 24, both of said gears being mounted on a vertical shaft 25 journaled on the machine frame. The two miter gears 23 and 24 slide on a feather on the vertical shaft 25 mounted in bearings carried 15 by the frame.

A U-shaped collar 26 is placed between one or the other of said gears and its respective bearing 7 to suit the propeller which is being machined. The vertical shaft 20 25, driven by one or the other of these miter gears 23 and 24, is threaded, as indicated at 27, to receive a sleeve 28 which is moved longitudinally up or down by the shaft 25 during its rotation. The sleeve has a forked 25 arm 29 which fits over a vertical guide 30 at the side of the boring mill in order to prevent rotation of the sleeve 28. The sleeve 28 carries a pivot slide bearing 31 through which passes the reversing rod 32 which 30 controls the reversal of the machine by means of a bell crank 33 on a rocker shaft 34 and the bell crank 33 has a handle 35.

36 designates a connecting rod extending from the arm 37 of the bell crank to the 35 reversing mechanism that belongs to the boring mill drive, it being apparent that the length of stroke of the reversing rod is controlled by the upper and lower set collars 38 and 39 on the reversing rod 32. The lower 40 end of the vertical shaft 25 is mounted in a step bearing 40 on the frame 3 of the machine and the upper bearing 41 is fastened to the face of the cross rail 42, see Figure 2, it being apparent that the rotation of the 45 vertical shaft 25 is transmitted to a horizontal shaft 43 mounted on the cross rail through the medium of the miter gear 44 carried by the shaft 25 and the miter gear 45 carried by the horizontal shaft 43 which 50 latter transmits the motion through the worm 46^x to the worm wheel 46 see more particularly Figure 10.

47 designates the cutting or tool carrying head. To install the cutting head 47 it is 55 necessary to move one of the tool heads, as 48, to the center of the cross rail 42 and remove the tool post and guides down to the face plate. A vertical bearing 50 is placed on the face plate in substitution for the tool 60 head of the boring mill and this bearing is provided with a sleeve bushing 51 which is free to revolve in the said bearing 50. This bushing is flanged at its upper end, as at 52, so that the hub 53 can be rigidly connected 65 in any desired manner to the worm

wheel 46. The worm wheel has fixed to it a feed nut 54 which carries the feed screw 55 for raising and lowering the cutter head 47, it being apparent that said worm wheel 46 is driven by the worm 46^x mounted on the 70 horizontal shaft 43 which is mounted in bearings 56 carried by the cross rail 42, see Figures 1 and 10. The feed screw 55 is tapered at its lower end 57 to fit into the tapered bore of the cutter head 47 and is held 75 in place by a steel nut 58 in threaded engagement with the lower extremity of said feed screw. The feed screw is threaded for a portion of its length, as indicated at 59, sufficient for the operation of the mill. The 80 feed screw 55 is hollow throughout its length and through it extends a rod 60 provided at its upper end with a shackle 61 to which is connected a counterbalance 61^x in order to relieve the screw 59 from excessive pressure 85 on the return stroke. The rod 60 which extends through the hollow feed screw 55 is fastened at its lower end to a guide shaft 62 which is tapered at its upper end as at 63 to fit the internal corresponding taper 90 in the lower end 57 of the stem 55. The guide shaft 62 fits in the bore of the tapered bushing 7 of the propeller hub 8 to hold the tool head in axial alignment with the propeller. 95

The cutting head 47 is preferably in the form of a spider and has tool posts 64 having a number of arms solid or adjustable to the propeller 9 that is to be machined. Each arm is provided with guides 65 on which is 100 slidable a tool carrying head 93 provided with a nut 94 through which the feed screw 66 passes in order to effect the proper adjustment of a tool post 64.

One of the arms of the cutter head, as 67, 105 is provided with a support 68 which carries a bracket 69 which is guided by the tool post 70 of the head of the boring mill, since such bracket is forked or bifurcated at its extremity, as at 71, in order to engage the guide 110 flange 72 of the tool post 70 and prevent rotation of the cutter head 47 and to serve as a guide for the cutter head during its vertical movement. In the forked end 71 is placed a casting 73 forming a part of the 115 bracket 69 and held in place in relation to the forked member 71 of the bracket 69 by a shaft 74 threaded through the casting there being a short travel of this casting on said threaded shaft 74 between the arms of 120 the fork sufficient to permit a small movement of the head 47 and thereby to provide a clearance for the tools on their return stroke, the fork 71 being machined so as to accurately fit over the guide flange 72 of the 125 tool post 70. The threaded shaft 74 carries a miter gear 75 which is in mesh with a miter gear 76 on a vertical shaft 77 which has a feather-way 78 which extends the entire length of the shaft. 130

The shaft 77 is keyed to a bevel gear 79 mounted in the tool carrying head 80 so that longitudinal movement of the shaft 77 is permitted. The gear 79 meshes with a 5 bevel gear 81 secured to a shaft 82 carried by the head 80 and provided with a worm wheel 83 which is driven by the worm 84 on the shaft 85.

86 designates an arm secured at one of its 10 ends to the end of the feed shaft 85 and at its other end to a connecting rod 87 eccentrically connected to a friction disk 88 which is loosely mounted on the drive shaft 89 of the machine feed and bears against a 15 friction disk 90 fixed to such shaft, said friction disk moving back and forth as the mill revolves, and the distance of travel for the clearance being controlled by stops 91 suitably placed on the friction disk 88 and 20 contacting with the bracket 92.

The tool head on the boring mill which is used as a stop for the cutter head 47 is used to transmit power to the clearance mechanism, taking it through the shaft 82 25 which is used for the hand operation of the tool post when the boring mill is used in its normal position, then through the feed operating shaft 85 at the right hand side of the cross rail 42.

30 The tool posts 64 have passing through them the bolts 95 which are adjustable in a slot 96 in the tool carrying head 93. An adjusting screw 97 is provided in threaded engagement with the bolt 95 and rotatably 35 carried by a portion of a tool carrying head 93 in order to enable the vertical adjustment of the tool post 64. The adjusting screw 97 is fixed in its adjusted position by means of the nuts 98 one of which serves as a lock 40 nut, it being seen that the adjusting screw 97 is provided with a shoulder which limits its movement in one direction.

It will be seen that the reversing rod 36 45 controls the belts of the reversing mechanism 99 which is of any desired or conventional type and driven from the motor 100. The reversing mechanism is on a stud shaft 101 which is provided with a pulley 102 around which passes a belt 103 which also 50 passes around a pulley 104 secured to the shaft 18. 105 designates the working tool carried by the tool post 64 in any desired manner.

The operation of the machine will now be 55 readily apparent to those skilled in this art and is as follows:—

The propeller which is to be faced is secured to the worm wheel 1 in the manner hereinbefore described and the working tools 60 105 are secured in their proper adjusted position.

The operator now starts the machine by means of the handle 35 which through the connecting rod 36 shifts the belts to cause 65 the motor 100 to drive the shaft 18 which is

connected by means of suitable gearing as described with the gear 1 on which the propeller is mounted. The shaft 25 is now rotating, thereby causing the vertical movement of the sleeve 28 which travels in the 70 path of the adjustable stops 38 and 39. The contact of the slide bearing 31 with one of these stop rocks the bell-crank lever 33, causing the propeller to be moved in a reverse direction.

75 It will be noted from the foregoing that an oscillatory movement is imparted to the propeller and during this oscillatory movement of the propeller the tool carrying head 47 is raised and lowered, since the shaft 25 80 is intergeared with the shaft 43, which latter rotates the worm wheel 46, thereby rotating the feed nut 54 and causing the vertical movement of the feed screw 59, which is operatively connected with the tool carrying head 47 to raise and lower it during the oscillatory movement of the gear 1 on which the propeller is mounted. By proper timing of the gears the cutter head 47 rises and falls to suit the pitch of the propeller.

90 I provide means to effect a clearance between the propeller and the cutting tools. The shaft 89 which is intergeared with the shaft 18 causes the friction disc 90 to revolve thereby causing the revolution of the 95 friction disc 88 which is loosely mounted on the shaft 89. The friction disc 88 is connected to the connecting rod 87 which latter actuates the shaft 85 thereby rotating the shaft 82 and the shaft 77. This rotation of 100 the shaft 77 rotates the shaft 74, see Figure 6, thereby imparting a lateral movement to the tool carrying head 47 so that the cutting tools at each end of their stroke will clear the propeller.

105 It will be apparent that the rotation of the friction disc 88 will be arrested when one of the stops 91 contacts with the stationary bracket 92.

By means of change gears the machine 110 can be adapted to various pitches of different propellers.

The movement of a tool post is manually controlled by rotating a feed screw 66. The machine can be readily adapted to finish a 115 right or a left hand propeller owing to the provision of the gears 23 and 24 and the spacing collar 26, see Figures 4 and 5. When the spacing collar is in position the gear 24 meshes with the gear 22 and, when 120 the spacing collar 26 is removed, the gear 23 is fixed in such position on the shaft 25 that it will mesh with the gear 22.

125 It will be apparent that in accordance with my present invention, I am enabled to finish at the same time a plurality of blades of a propeller and by a single adjustment of the machine, it can be readily and quickly changed to conform to a propeller of a different pitch or to a right or left hand 130

propeller. The length of stroke of the oscillatory gear 1 which forms a support for the propeller can be varied by adjustment of the set collars 38 and 39 on the reversing 5 rod 32.

While I have described my invention as being formed by making material changes in a vertical boring mill in order to adapt it for the work intended, it is of course to be 10 understood that the machine in practice would be constructed as a concrete unitary structure, the embodiment shown being only for the purpose of illustrating one manner of carrying out my invention in practice.

15 It will now be apparent that I have devised a novel and useful construction of a machine for facing propeller blades which embodies the features of advantage enumerated as desirable in the statement of the 20 invention and the above description, and while I have, in the present instance, shown and described a preferred embodiment thereof which will give in practice satisfactory and reliable results, it is to be understood 25 that such embodiment is susceptible of modification in various particulars without departing from the spirit or scope of the invention or sacrificing any of its advantages.

Having thus described my invention, what 30 I claim as new and desire to secure by Letters Patent, is:—

1. In a machine for facing propeller blades, an oscillatory support for the propeller, and means aligned by the propeller 35 to face a blade of the propeller during the oscillation of said support.

2. In a machine for facing propeller blades, a support for the propeller, means to oscillate said support, a cutter head in axial 40 alignment with a propeller on said support, cutting tools adjustably mounted at opposite sides of said cutter head, and means to raise and lower said tools to suit the pitch of the propeller blade during the oscillation of 45 said support.

3. In a machine for facing propeller blades, a support for the propeller, means to oscillate said support, cutting tools, means to raise and lower said tools to suit the 50 pitch of the propeller blade during the oscillation of said support, and means to effect a clearance between the cutting tools and the blades of the propeller being faced.

4. In a machine for facing propeller 55 blades, a support for the propeller, means to rotate said support, means to adjust said rotating means for the facing of right or left-hand propeller blades, cutting means, devices controlling relative movement between 60 the propeller on said support and the cutting means, and reversing mechanism for said rotating means controlled by said devices.

5. In a machine for facing propeller 65 blades, a support for the propeller, means to

rotate said support, means to adjust said rotating means for the facing of right or left-hand propeller blades, cutting means, devices controlling relative movement between the propeller on said support and the cutting 70 means, and reversing mechanism for said rotating means automatically controlled by said devices.

6. In a machine for facing propeller blades, a support for the propeller, means to 75 rotate said support, cutting means, devices controlling relative movement between the propeller on said support and the cutting means, reversing mechanism for said rotating means automatically controlled by said 80 devices, and clearance mechanism to cause the cutting means to clear the propeller at the end of each cut.

7. In a machine for facing propeller blades, an oscillating support for the propeller, actuating means for it, a cutter head, means to prevent said head from rotating, an automatically actuated feed screw to raise and lower said head in conformity to the 85 pitch of the propeller being faced, and a counterbalance for said feed screw.

8. In a machine for facing propeller blades, a propeller support mounted to revolve in a horizontal plane, means to oscillate said support, a cutting head maintained 90 in axial alignment by the propeller being faced, cutters adjustably carried thereby, a feed screw to raise and lower said head, and means to actuate said feed screw.

9. In a machine for facing propeller 100 blades, a support for the propeller mounted to revolve in a horizontal plane, a cutting head in axial alignment with said support, means to oscillate said support, cutters carried by said head, means to feed said cutters, and means to raise and lower said cutting head, in accordance with the pitch of the propeller.

10. In a machine for facing propeller blades, an oscillatory support for the propeller, actuating means for such support, a gear train to suit the pitch of the propeller being faced and driven from said actuating means, means to adjust said gear train for right or left-hand propeller blades, and propeller facing mechanism controlled by said 110 gear train.

11. In a machine for facing propeller blades, an oscillatory support for the propeller, actuating means for said support, a cutter head having a member housed within the hub of said propeller to maintain the cutting head in proper alignment, cutting tools carried by said cutting head and means to raise and lower said cutting head in conformity to the pitch of the propeller being faced.

12. In a machine for facing propeller blades, a support for the propeller, means to 120 rotate the support in one direction, means to 125

- adjust said rotating means for right or left-hand propeller blades, a train of gears to actuate the support in a reverse direction, reversing mechanism controlled by said train 5 of gears, and means operatively connected to said train of gears to face the propeller.
13. In a machine for facing propeller blades, a gear rotatably mounted and adapted to receive a propeller, a cutter head in axial alignment with said propeller, a feed screw connected with said head, cutting tools on said head, means to actuate said feed screw in accordance with the pitch of the propeller to be faced, and means to oscillate said gear and thereby the propeller.
14. In a machine for facing propeller blades, a driving shaft, a gear operatively connected with it and adapted to support a propeller, friction discs on said shaft, propeller facing means, means to relatively move said facing means and propeller to face the propeller, and clearance mechanism controlled by one of said friction discs to cause the cutting means to clear the propeller at each end of the cutting stroke.
15. In a machine for facing propeller blades, an oscillatory support to receive the propeller, actuating means for said support, cutting mechanism in axial alignment with the propeller on said support, time gearing operatively connected with said cutting mechanism to actuate it, and reversing mechanism for said support actuating means and automatically controlled in accordance with the movement of said cutting mechanism.
16. In a machine for facing propeller blades, an oscillatory support to receive the propeller, means to oscillate said support, a cutter head in axial alignment with the propeller and guided by it, cutting tools carried by said cutter head, means to feed said cutting tools, and means to raise and lower said cutter head during the oscillation of said support.
17. In a machine for facing propeller blades, a support to receive the propeller, a shaft guided in said propeller, a cutter head into which said shaft extends, a counterbalance connected with said shaft, cutting tools adjustable on said cutter head, a feed screw 50 connected with said cutter head, means to actuate said feed screw in accordance with the pitch of the propeller to be faced, said means being adapted to control the direction of rotation of said support, and means 55 to rotate said support.
18. In a machine for facing propeller blades, an oscillatory support for the propeller, driving means for said support, a cutter head, cutting tools carried by it, means 60 to raise and lower the cutter head during the movement of said support, means to prevent rotation of said cutter head during the cutting stroke, and means to impart a partial revolution to the cutter head at the end 65 of each stroke.
19. In a machine for facing propeller blades, an oscillatory support to receive the propeller, actuating means for said support, a cutter head, cutting tools carried by said 70 head, means to raise and lower said head in accordance with the pitch of the propeller to be faced, and devices connected with said cutter head and controlled by said support actuating means to impart a partial rotation 75 to said cutter head at the end of an oscillatory stroke of said support.
20. In a machine for facing propeller blades, an oscillatory support to receive the propeller, a cutter head mounted for vertical 80 movement, cutting mechanism carried by said head, means to raise and lower said cutter head, a guide for said cutter head to prevent its revolving, a shaft in threaded engagement with said cutter head, and means 85 to actuate said shaft to partially rotate said cutter head at the end of each oscillation of said support.

FRANK EGON NEITZEL.
